UNITED STATES PATENT OFFICE.

EVEN J. ROHNE, OF MINNEAPOLIS, MINNESOTA.

ELECTRIC HEATER FOR STEERING-WHEELS.

1,345,249.

Specification of Letters Patent. Patented June 29, 1920.

Application filed September 7, 1917. Serial No. 190,264.

To all whom it may concern:

Be it known that I, EVEN J. ROHNE, a citizen of the United States, residing at Minneapolis, in the county of Hennepin and 5 State of Minnesota, have invented certain new and useful Improvements in Electric Heaters for Steering-Wheels; and I do hereby declare the following to be a full, clear, and exact description of the invention, such 10 as will enable others skilled in the art to which it appertains to make and use the same.

My invention has for its object to provide an extremely simply and highly efficient electric heater, or warming device, for the steering wheel, or other hand piece of a steering device for automobiles; and, to the above end, generally stated, the invention consists of the novel devices and combinations of devices hereinafter described and 20 defined in the claim.

In the accompanying drawings, which illustrate the invention, like characters indicate like parts throughout the several 25 views.

Referring to the drawings:

Figure 1 is a plan view showing the improved electric heater applied to the steering wheel of an automobile;

30 Fig. 2, is a sectional view taken on the line 2—2 of Fig. 1;

Fig. 3, is a detail view in section taken on the line 3—3 of Fig. 1 on an enlarged scale;

35 Fig. 4, is a diagrammatic view showing the wires and heating element of the electric heater.

Fig. 5, is a view principally in transverse section showing the electric heater removed from the steering wheel and spread out flat; 40 and

Fig. 6 is a detail view taken on the line 6—6 of Fig. 5.

The numeral 7 indicates the rim, and the 45 numeral 8 indicates the hub and arms of a steering wheel, such as are generally used in connection with automobiles. It may be here stated that the term "automobile" is herein used in a broad sense to include any motor driven vehicle.

50 The electric heater proper is flexible in all directions and comprises a casing 9, a heating element 10, in the form of a bare wire bent back and forth upon itself to form long substantially parallel loops, and two 55 insulating cover plates 11 for said heating element. The casing 9 may be made from

leather, cloth, pantasote or other suitable flexible material that, as shown, is folded upon itself and stitched at its edges to form said casing. Secured in each longitudinal 60 edge portion of the casing 9 is a row of eyelets 12. The cover plates 11, for the heating element 10, may be made from a single piece of canton flannel or other suitable fabric folded upon itself and placed in the casing 9 to insulate the heating element 10 therefrom. These cover plates 11 are stitched to connect the same between the members of each loop of the heating element to separate and thereby insulate said 65 members from each other and hold the same 70 properly spaced.

As shown, there are two of the improved electric heaters applied to the rim 7 of the steering wheel by folding the same there-around and at diametrically opposite points and securing said heaters thereto by laces 75 13. These laces 13 are run through certain of the eyelets 12 and passed, as shown, around the casing 9, and hence the rim 7 80 with their ends tied together. By passing the laces 13 around the casings 9, better grips or hand-holds are provided for the operator, as they prevent his hands from slipping. As the electric heaters are flexible 85 in all directions they will when laced onto the rim 7 closely fit the same. To one of the longitudinal edges of the casing 9 is secured a flap 14, which, when the electric heater is secured to the rim 7, extends under the other longitudinal edge thereof and closes the gap between said two edges. Conducting wires 15 connect the terminals of the heating element 10 with a battery 16 90 or other source of electrical energy which in automobile service may be a generator, magneto or battery, according to the type 95 thereof.

From the above description, it is evident that by passing the laces 13 around the casings said laces not only afford better hand holds, but secure the heaters on the rim in a manner that prevents the same from moving and thereby causing wear due to friction. It is also evident that the laces 13 100 protect the casings 9 from wear under the grip of the operator.

The above described electric heater is of comparatively small cost to manufacture, with no metal parts to come in contact with 110 the heating element and thereby form a short circuit. Said heater may be easily

applied to or removed from a steering wheel rim, or the like, and furthermore it is highly efficient for the purpose had in view.

What I claim is:

- 5 A heating pad for steering devices comprising a flexible heating element, a pair of flexible insulating cover plates between which the heating element is placed, a flexible casing for the insulating plates, the longitudinal edge portions of which are extended outward of the insulating plates, eye-
- 10

lets connecting both the inner and outer longitudinally extended edge portions of the casing, and a lace adapted to be inserted through the eyelets for connecting the longitudinal edges of the casing. 15

In testimony whereof I affix my signature in presence of two witnesses.

EVEN J. ROHNE.

Witnesses:

EVA E. THOMPSON,
HARRY D. KILGORE.
